ABSTRACT OF THE DISCLOSURE

A hydraulic centrifugally operated governor wherein a power piston is operated only by oil pressure in the fuel increasing direction and only by return springs in the fuel decreasing direction. A floating lever is engaged with the power piston and a slider, connected to a link, is engaged to a movable fulcrum of an eccentric shaft and a speeder spring is disposed between the link and fly weights of the governor. A compensator piston operatively connected to the power piston includes two equal springs acting on a push rod in a chamber which is in communication with an oil reservoir through a needle valve, and also with a pilot valve which controls the flow of oil to the power piston chambers.

The present invention relates to and has for its object to provide a hydraulic governor which is attached to a row-type fuel injection pump, which governor has a very high range of controlling characteristics, an extremely wide range of regulation and is suitable for use in all diesel engines.

In order that the present invention may be more readily understood, reference will now be made, by way of example, to the accompanying drawings, in which:

FIG. 1 is a schematic diagram of a hydraulic governor in transverse section according to the present invention.

FIG. 2a is a detailed perspective view of a speed regulation and fluctuation rate mechanism and FIG. 2b is a simplified diagram thereof.

FIG. 3 is a detailed perspective view of a compensator mechanism.

Referring now to FIG. 1, the governor according to the invention is directly attached to a fuel injection pump 1, actuated by a cam shaft 2 to which is fixed a speed acceleration gear 3 adapted to rotate a pilot valve bushing 4 having ports 4a, 4b, and 4c at the speed of acceleration gear 3. To one end of said pilot valve bushing 4, there is connected a gear shaft 6 of a gear pump 5 which serves to deliver oil at working pressure from a source to the hydraulic governor and on the other are fly weights 7 for detecting the speed of rotation of the governor, respectively, these being rotated at the same speed of rotation as the pilot valve bushing 4. In the pilot valve bushing 4 is provided a pilot valve 8 movable in the axial direction by the centrifugal force of the fly weights 7 and by said pilot valve 8 to control the working oil between the gear pump 5 and a power piston 9 controlling the fuel injection pump 1. The fly weights 7 engage the pilot valve 8 through a thrust bearing and a speeder spring 10 is afforded a preset load opposite to the centrifugal force corresponding to the speed of rotation of the fly weights. The pilot valve 8 is provided such that a valve portion 8a of the pilot valve 8 may close the port 4b of the pilot valve bushing 4 when the speed of rotation of the engine is in a balanced condition, and thus the fly weights 7 and the speeder spring 10 are balanced in force, but with an increase in the load on the engine and the resultant decrease in the speed of rotation of the bushing 4 the centrifugal force of the fly weights 7 is less than the load of the speeder spring 10 so that the pilot valve 8 shifts to the right from the position shown in FIG. 1 and both ports 4a and 4b are connected to each other. The working

2

oil from the gear pump 5 flows into a cylinder in which the power piston 9 operates and moves the power piston 9 to the right side from the position shown in FIG. 1, that is, in the increasing direction of fuel feed. Inversely when the load on the engine is reduced the centrifugal force of the fly weights 7 increases so that the pilot valve 8 moves to the left side from the position shown in FIG. 1 and the ports 4b and 4c are connected to each other so that flow of the working oil in the rod end of the power piston cylinder will be directed into a governor oil reservoir since the power piston 9, by the force of two strong and weak return springs 11 and 12, respectively, on the opposite sides of said piston, is moved to the left from the position shown on the drawings, that is, in a decreasing direction of fuel feed. In other words, the governor of the present invention operates the power piston 9 by oil pressure only in the increasing direction of fuel feed and the operation in the fuel decreasing direction is carried out by the two return springs 11 and 12. Then, between the gear pump 5 and the pilot valve 8, there is provided a check valve 13 and an accumulator 14 for maintaining a constant pressure. The accumulator 14 consists of a movable piston and a spring and serves to maintain the constant pressure of the working oil and at the same time makes up the deficiency of feeding capacity of the working oil of the gear pump 5 upon a sudden variation of load. The forward end of a rod of said power piston 9 is provided with a pin 15. On the fulcrum of a movable pivot 16a of eccentric shaft 16, there is provided a floating lever 18 having long grooves at one end engaged to the pin 15 and at the other end engaged with a slider 17 sliding in the interior. To this slider 17 is connected a link 19 having a pin 19a. The other end 19b of the link 19 is connected to a fork link 20 which rotates about a control lever shaft 20a. The eccentric shaft 16 may be provided with a scale device 21. The fork link 20 is provided with a control lever 22. Between the two fulcrums of the link 19 is connected the speeder spring 10 through the spring fork 23 carried on a pivot 19c. The operation of this mechanism will now be explained. Hereinafter, reference to the direction of movement of elements, such as to the right or left will be understood to be with respect to FIG. 1 of the drawings. The speed adjustment of the governor is made by operation of the control lever 22, whereby the speeder spring 10 is deflected correspondingly. As its load is varied the engine speed is varied accordingly. When the control lever 22 is fixed and the speed of rotation of the engine is reduced under a predetermined load, the power piston 9 is transferred in the decreasing direction of fuel feed that is, to the left side for stopping the rise of the speed of rotation of the engine. Movement of the power piston 9 rotates the floating lever 18 about a movable fulcrum 16a of the eccentric shaft 16 and the slider 17 at the lower part of the floating lever 18 moves to the right side. As the lower fulcrum 19b of the link 19 is fixed the fulcrum 19c also moves to the right side and the speeder spring 10 is deflected and provided with a new preset load. By this increased set load the power piston moves to the left side by an increase of the centrifugal force of the fly weights 7 and this pushes the pilot valve 8 to a position at which the ports 4a and 4c are connected to move again to positions to the closing of the port 4b, balancing with the centrifugal force of the fly weights 7 at a speed of rotation slightly above the initial balanced condition thereby setting it as this speed of rotation. By this link mechanism it is possible to obtain the fluctuation ratio of speed. Inversely when the load on the engine is increased the movement of the power piston 9 in the increasing direction of fuel feed extends the speeder spring 10. In consequence, adjustment

is made at a position corresponding to a slightly lower speed than that in the balanced condition at the initial rotation speed. Assume that speed of rotation in the balanced condition is N_0 and the speed of adjusted rotation is N_1 .

$$\text{fluctuation ratio of speed } \epsilon = \frac{N_1 - N_0}{N_0} \times 100$$

ϵ in the above formula will be determined by the lever ratio of the above described link mechanism. If, as shown in FIG. 2b, displacement of the power piston 9 is given as x ; amount of deflection of the speeder spring 10 as y ; and distances between the link fulcrums, the pin 15, the movable fulcrum 16a, the pin 19a, the lower fulcrum 19b, and the fulcrum 19c, as l_1 , l_2 , l_3 , and l_4 , respectively, the following formula will be obtained:

$$y = \frac{l_2}{l_1} \cdot \frac{l_3}{l_4} \cdot x$$

in which it is noted that y is large so long as ϵ is large. This formula shows that as the pilot valve 8 rapidly closes the port 4b by a large displacement of y the balance of the engine load and the engine output is obtained at a value much higher or lower than in the case where N_1 has smaller y . Herein, as l_3 and l_4 are constant, y is determined by l_1 , l_2 (l_1+l_2 constant) which is determined by rotation of the eccentric shaft 16. Thus, when the movable fulcrum 16a of the eccentric shaft 16 and the pin 19a of the link 19 are in agreement $l_2=0$. As the movement of the pilot valve 8 through the speeder spring 10 by y is not restricted the pilot valve completely follows the variation of speeds of rotation, therefore, ϵ can be made zero.

On a connecting part 24a of a connecting rod 24 extending to the right end of the power piston 9 and the control rack of the fuel injection pump 1, there is provided another link 25, which moves on a movable fulcrum 26a of an eccentric shaft 26, wherein the movement of the power piston 9 is transmitted to a push rod 27 for operating the compensator mechanism. This movement of the push rod 27 is transmitted through resiliency of springs 28 to a compensator piston 29 provided in the middle of said two equal springs 28 so that the chamber on the left side of piston 29 pressurizes or expands and the oil in the chamber is led to a chamber at the right end of the pilot valve 8 and to a needle valve 30 and further through the needle valve 30 to the governor oil reservoir. The eccentric shaft 26 may be provided with a scale device 31. Accordingly, when the speed of input rotation of the governor rises the power piston 9 moves in the decreasing direction of fuel feed so that the link 25 rotates counterclockwise at the fulcrum 26a and the compensator piston 29 moves to the right by the force of the spring 28. Therefore, the volume of the chamber to the left of piston 29 increases and oil flows from the governor oil reservoir through the needle valve 30. When the flowing oil is throttled by the needle valve 30 there is generated a negative pressure in the chamber, which actuates the pilot valve 8 to the right side or opposite to the centrifugal force of the fly weights 7 so as to temporarily close the once opened port. Thereby it is possible to delay somewhat the action of the power piston 9 relative to the variation of input or the responsiveness thereof. Inversely when the speed of input rotation is lowered the piston 29 is pushed by the push rod 27 through the spring 28 so that positive pressure is generated to similarly delay the responsiveness. This action serves to prevent the sudden variations of the speed in rotation of the engine caused from a sudden variation of an engine load and in generation of hunting to obtain a stable performance.

As hereinbefore described, the present governor has two feedback elements in use as a speed regulation ratio mechanism and a compensator mechanism, the effects of which mechanisms can be widely and simply adjusted

from outside of the governor by the eccentric shafts 16 and 26 and the needle valve 30.

Besides, the governor of the invention, when it is attached to the fuel injection pump 1 for equipment in the engine, has a drag spring 32 for compression in the power piston 9 to adjust the change of position of the fuel rack as required for the output and purpose of the engine, to which spring is connected a control rack of the pump 1 through the connecting rod 24, and a stopper 37 for stopping the control rack at a predetermined position on the side opposite to the governor of the pump, whereby the position of the full rack can be simply adjusted in what engine it may be used.

Other characteristics of the present governor lie in that the operation in the decreasing direction of fuel feed is made by means of two return springs 11 and 12 so that there is provided a valve for letting the pressurized oil in the cylinder escape effecting the simple stoppage of an engine in whatever position the control lever may be set. This principle is incorporated in a stopping shaft 33 which operates a rotary valve, to the outer end of which shaft 33 is attached a stop lever 34. The lever 34 may be turned in 90° (or less) by which action the cylinder having the power piston 9 and the oil reservoir of the governor are passed through a valve to release the pressurized oil of the cylinder so that the control rack is moved back to a zero position and the engine is stopped. This mechanism is an engine stopping device to be manually operated. In addition, it is possible to equip an electromagnetic valve or a piston 35 and an electromagnet 36 as shown in FIG. 1 and stop the engine by remote control.

As the centrifugal force of the fly weights 7 of the present governor is small and the speeder spring 10 is weak so that it is possible to make the reactionary force of the control lever 22 very small, said lever 22 is operated by a small motor to remote control speed setting of the engine.

As described above, the governor of the present invention has high controlling characteristics, is extremely wide in the range of adjustment and is an all speed governor with which it is possible to remotely control the engine so that it is suitable for all kinds of engines for general industrial use in ship building, electric generation and the like and construction use and the other general objects.

Many variations may be effected without departing from the spirit of the present invention. It is to be understood that these, together with other variations in details, are encompassed within the appended claims.

I claim:

1. A hydraulic governor comprising: a power piston for controlling a fuel feed pump, a pilot valve bushing which is rotatable about its axis, fly weights operatively connected to the pilot valve bushing to move outwardly in response to an increase in the speed of rotation of the pilot valve bushing, shaft means for operatively connecting the pilot valve bushing to a gear pump to operate the pump by rotation of the pilot valve bushing, a pilot valve slidably axially within the pilot valve bushing, said pilot valve being operatively connected to the fly weights to undergo said axial sliding movement in one direction in response to the application of centrifugal force to the fly weights, and a speeder spring for urging the fly weights to their retracted positions and hence causing the pilot valve to move in the opposite direction, a passageway between the gear pump and the power piston, said passageway being controlled by the axial position of the pilot valve, said power piston being movable in the fuel feed increasing direction only under the influence of pressurized liquid and movable to the fuel feed decreasing direction under the influence of spring means, and a control means for regulating the operation of the power piston in response to changes in the speed and the fluctuation rate of speed, said control means comprising: a floating lever having

one end engaged to one end of said power piston and at its other end said floating lever being connected to one end of a slider which slider is connected to a link at its other end, said floating lever being mounted to turn about a variable fulcrum of an eccentric shaft, said link being in connection with a fork link which is in turn connected to a control lever, and said speeder spring connected to the link and extending therefrom to the said fly weights.

2. A hydraulic governor according to claim 1, comprising a further link connected to an end of the power piston and an end of a control rack of the fuel feed pump, said further link being carried on a variable fulcrum of an eccentric shaft and positioned to operate a push rod, a compensator piston mounted to be acted on by the push rod in a chamber housing and including two springs of equal strength located one on each side of said compensator piston, said push rod and said chamber being in fluid communication with an oil reservoir through a needle valve and also with the side of the pilot valve at which a pressure build-up would offset the force of the speeder spring.

3. A hydraulic governor according to claim 1 including a drag spring operatively mounted within the power piston and tending to urge the said power piston to the fuel decreasing position relative to the means which connects the power piston to the fuel feed pump.

4. A hydraulic governor according to claim 1 including a means for stopping the engine by releasing pres-

surized oil from the power piston, thus permitting the said spring means to urge the power piston without the resistance of pressurized fluid to the fuel feed decreasing position until the engine stops.

5. A hydraulic governor according to claim 2, including a drag spring operatively mounted within the power piston and tending to urge the said power piston to the fuel decreasing position relative to the means which connects the power piston to the fuel feed pump, and including a means for stopping the engine by releasing pressurized oil from the power piston, thus permitting the said spring means to urge the power piston without the resistance of pressurized fluid to the fuel feed decreasing position until the engine stops.
